UNITED STATES PATENT OFFICE.

CLARENCE P. HOLLISTER, OF NEW YORK, N. Y.

LUBRICATION OF INTERNAL-COMBUSTION ENGINES.

1,323,861.

Specification of Letters Patent.

Patented Dec. 2, 1919.

Application filed August 11, 1917. Serial No. 185,681.

To all whom it may concern:

Be it known that I, CLARENCE P. HOLLISTER, a citizen of the United States, residing at New York, in the county of New York 5 and State of New York, have invented certain new and useful Improvements in Lubrication of Internal-Combustion Engines, of which the following is a specification.

My invention relates to the lubrication 10 of internal combustion engines and more particularly to the lubrication of the rotary valves and the walls of sleeve valves.

In engines of the sleeve-valve type, there 15 is a very large surface area between the inner cylinder wall and the sleeve valve and between the latter and the compression sleeve or packing sleeve as well as between the piston and the inner wall of the sleeve valve and it is essential to maintain a film 20 of lubricating oil between each of these frictional surfaces. The main purpose of my invention is to provide an efficient system of lubrication and the construction of sleeve valves and packing sleeves which will effectively maintain a film of oil between the contacting surfaces.

In the accompanying drawings, Figure 1 30 is a vertical sectional view through the cylinder of an internal combustion engine showing an embodiment of my invention; Fig. 2 is a side elevation, partly broken away, of the sleeve valve; Fig. 3 is a transverse sectional view on the line 3—3 of Fig. 1; Fig. 4 is a side elevation, partly in section, of the compression or packing sleeve; Figs. 5 and 6 are fragmentary detail views; 35 and Fig. 7 is a developed diagram of the compression sleeve.

The engine cylinder 1, which may be provided with the usual jacket 2, to form a 40 passage 3 for the circulation of cooling water, is bolted at 4 to the base 5, constituting the crank case of the engine. The revoluble sleeve valve 10 rests upon a bearing ring 12, 45 carried by a web 14 extending inwardly from the upper part of the crank case.

The sleeve valve may be rotated at a speed 50 proportionate to the speed of the crank-shaft 17, in any suitable manner, as by means of a chain 18, connected to a sprocket wheel 19 keyed to the crank shaft and a sprocket 20 carrying the worm 21, in mesh with the gear teeth 23 on the sleeve valve.

The lubrication of the inner wall of the 55 sleeve valve may be effected in the manner commonly employed for the lubrication of

the cylinder, viz: by the oil continually dashed up from the supply in the crank case by the splash of the crank 24 therein. A portion of the oil passes through the holes 25 to the outer side of the sleeve valve, and into the spiral grooves 26. As the sleeve rotates, these spiral channels carry the oil upwardly into the annular groove 26^a, located substantially at the top of the sleeve portion and at the base of the valve portion. A portion of the oil in the grooves 26 is spread over the surfaces of the cylinder and the sleeve valve to effectually lubricate these surfaces with an oil film.

The cylinder head 30 projects within the cylinder below the ports and is provided with passages 31 and 32 registering respectively with the intake port 34 and the outlet port 35. The upper portion of the sleeve 75 valve is provided with ports 36, 37 which register alternately with the intake and exhaust ports.

In order to prevent leakage during the compression stroke and during the explosion of the gases in the explosion chamber of the cylinder head, I provide a packing sleeve or compression ring 40, which is disposed between the head and the valve sleeve, and provided with ports 31^a, 32^a registering 85 with passages 31, 32 in the head. The sleeve or ring is preferably provided with interior threads 41 of rectangular section to engage corresponding threads on the exterior of the head. Packing rings 42 prevent the possibility of any leakage around the top edge of the sleeve. The compression sleeve is held in fixed position by a screw pin 43, secured in the head and projecting into an aperture 45 in the compression sleeve.

I prefer to make the compression sleeve an integral ring or cylinder and to make it compressible by means of a series of slots 47 cut alternately from opposite edges and extending partially across. It is desirable to shut 100 off or close the slots extending from the top edge of the sleeve in order to prevent the escape of any gases during compression which might follow the inside wall of the sleeve from one of the passages 31, 32 and then 105 upwardly through these slots and over the top edge of the valve to one of the ports. I therefore cut a transverse slot and insert a closure plate 48, which may be welded at 48^a to hold it in place.

When the cylinder head with the surrounding compression ring 40 is inserted within

the sleeve valve, it is necessary to slightly compress the ring, and it then springs outwardly into close contact with the inner walls of the valve. It is quite important that the 5 engaging surfaces of the ring 40 and valve 10 should be kept well lubricated. For this purpose I provide shallow grooves or recesses cut into the outer wall of the compression sleeve, and cause the suction caused by 10 the downward stroke of the piston to draw oil thereinto. This system of grooves is shown in the developed diagrammatic view of the compression sleeve shown in Fig. 7. A main supply groove or channel 50 near 15 the lower edge of the sleeve, connects with branch grooves 51, 52, 53 and the latter connect with different series of smaller vertical grooves 56. The oil is drawn into the offset portion 50^a of the main channel 50 through an aperture 63, passing through the 20 wall of the sleeve in alignment with the annular groove 26^a, which is constantly supplied with oil by the spiral grooves 26, in the manner previously described.

25 A notch or channel 62 cut into the side wall of the depending head 30 adjacent the aperture 60 connects the latter with the bore of the cylinder. An aperture 63 extending through the wall of the sleeve valve and 30 into the annular groove 26^a comes into alignment with the offset portion or branch 50^a of the channel 50 during every revolution of the valve so that at this instant there is a direct connection between the groove 26^a and 35 the channel 50 in the wall of the compression sleeve or ring. The aperture 63 is so positioned in the valve wall that it will be in alignment with the offset groove portion 50^a at the instant the piston is starting upon 40 its downward suction stroke. For clearness of illustration, the aperture 63 is displaced from its true position in Fig. 1. Inasmuch as the channel 50 in the wall of the compression ring or sleeve communicates with the 45 bore of the cylinder through the aperture 60 and channel 62, it is evident that the downward suction stroke of the piston causes a partial vacuum in the channel 50 and offset portion 50^a and as the aperture 63 in the 50 sleeve valve comes into alignment with the offset groove portion 50^a, this will cause a small amount of oil in the groove 26^a to be drawn inwardly into the portion 50^a, from whence it flows into channel 50, and in this 55 manner a supply of oil will be maintained therein. The rotation of the sleeve valve around the compression ring 40 will cause the oil to pass from the channel 50 and offset portion 50^a into the branch channels 51, 60 52, 53 and 56 and from these the oil will be distributed over the entire surfaces of the sleeve valve and compression ring. In addition to supplying oil to the groove or channel 50, the suction through the aperture 63 65 in the annular groove 26^a assists in drawing

the oil upwardly through the spiral channels 26 in the outer wall of the sleeve valve.

I have shown a single aperture 63 passing through the wall of the sleeve valve but it will be understood that a larger number 70 may be employed if it is found desirable. I have given a detailed description of the particular construction illustrated in the accompanying drawings for the purpose of clearly disclosing my invention but it will 75 be apparent to engineers that various changes and modifications may be made within the scope of my claims and without in any manner departing from my invention.

I claim:—

1. A lubricating system for sleeve valves in internal combustion engines, comprising a rotatable cylindrical sleeve valve provided with a series of continuous channels in the 85 outer wall, an oil supply connected therewith, and means for connecting the channels with the upper end of the cylinder chamber during a portion only of the suction stroke of the piston.

2. A lubricating system for sleeve valves in internal combustion engines, comprising a rotatable cylindrical sleeve valve provided with a continuous spiral channel in the outer wall, apertures in the lower portion of the 95 sleeve valve adapted to convey oil from the inner to the outer sides thereof, and means for connecting said channel with the upper end of the cylinder chamber during a portion only of the suction stroke of the piston.

3. In an internal combustion engine having a sleeve valve having an upper portion provided with valve openings and a lower cylinder portion, means for lubricating the inner and outer walls of the sleeve valve, 105 comprising means for delivering oil to the inner portion thereof extending within the engine cylinder, an aperture extending through the sleeve to deliver oil from the inner side to the outer side, channels in the 110 outer wall of the sleeve adapted to carry the oil upwardly, a cylinder head extending within the upper portion of the sleeve valve and provided with ports in alignment with the inlet and outlet ports of the engine with 115 which the valve openings register alternately, a compression ring intermediate said head and the upper valve portion of the sleeve valve, said ring having oil grooves in its outer periphery, an aperture through 120 said ring and communicating with the cylinder chamber, and an aperture in the wall of said sleeve valve adapted to align with a portion of the oil grooves in said ring during the movement of the sleeve valve, whereby the suction of the piston causes the oil to flow from the channels upon the outside of the sleeve valve into the oil grooves in the compression ring to thereby lubricate 125 the contacting surfaces of the ring and valve.

4. In an internal combustion engine having a head depending within the cylinder and provided with inlet and exhaust passages, a sleeve valve provided with valve openings adapted to register alternately with said passages, and a compression sleeve or ring intermediate said head and valve and expanding into contact with the latter, said ring having openings in alignment with said passages, and being provided, with oil grooves upon its outer periphery and with an aperture extending through its wall and communicating with the cylinder chamber, whereby the suction of the piston causes a partial vacuum in said grooves.
5. In an internal combustion engine having a head depending within the cylinder and provided with inlet and exhaust pas-
- 20 sages, a sleeve valve provided with valve openings adapted to register alternately with said passages, and a compression sleeve or ring intermediate said head and valve and expanding into contact with the latter, said ring having openings in alignment with said 25 passages, and being provided with oil grooves upon its outer periphery and with an aperture extending through its wall and communicating with the cylinder chamber, whereby the suction of the piston causes a partial vacuum in said grooves, said sleeve 30 valve having an aperture adapted to register with a portion of the oil grooves in said compression ring.

In testimony whereof I affix my signature.

CLARENCE P. HOLLISTER.
